(57) CLAIM

The ornamental design for a container for perfumes and cosmetic products, as shown and described.

DESCRIPTION

FIG. 1 is an exploded view of a container for perfumes and cosmetic products showing my new design; FIG. 2 shows a front elevation view thereof; FIG. 3 shows a rear elevation view thereof, being a mirror image of the front elevation view of FIG. 2; FIG. 4 shows a left side elevation view thereof; FIG. 5 shows a right side elevation view thereof, being a mirror image of the left side elevation view of FIG. 4; FIG. 6 shows a top plan view thereof; and, FIG. 7 shows a bottom plan view thereof. The broken lines in FIG. 7 are for illustrative purposes only and forms no part of the claimed design.
